METHOD OF MAKING 8-HYDROXY-
QUINOLINE

Nathaniel Grier, Brooklyn, N. Y., and Charles Casalbore, Passaic, N. J., assignors to Dar-Syn Laboratories, Inc., Hawthorne, N. J., a corporation of New Jersey

No Drawing. Application January 7, 1948,
Serial No. 1,068

14 Claims. (Cl. 260—289)

1 The present invention is directed to the manufacture of 8-hydroxy quinoline and more particularly to an improved process resulting in a high yield of the product.

8-hydroxy quinoline is of considerable value in industry as a raw or intermediate material for the manufacture of derivatives thereof and for various other purposes. A number of methods for its production have been proposed and used but none of them has been completely satisfactory. For instance, one method involved the reaction of o-nitrophenol or o-aminophenol with glycerine. This process was very inefficient and maximum yields of 30 to 40% based on the initial ingredients were obtained. The reactants were relatively expensive, and in view of the unsatisfactory yield, this process is of limited use.

Other proposed processes involved the reaction of 8-chloro-quinoline with ammonia, followed by a sulphuric acid treatment. Another process consisted in the demethylation of 8-methoxyquinoline. While the yields of the 8-hydroxy quinoline were more satisfactory than in the above mentioned process, the overall yield was extremely low because the starting materials are obtainable only in poor yield.

Still another process which has been found of some use in industry involves the reaction of quinoline-8-sulfonic acid with sodium hydroxide. The starting material was mixed with the sodium hydroxide and a very substantial amount of water whereby solution of the sodium hydroxide took place and the reaction mixture was heated until the mass became fused. This required a considerable length of time and after the reaction was complete, the molten material was allowed to solidify and was broken up physically. It was then dissolved in hydrochloric acid and the 8-hydroxy quinoline was steam distilled to purify the same. The temperature of the fusion and reaction was probably between 190° and 200° C. While it was claimed that a 50% yield was obtainable thereby, actual experience shows that the yields were only from 20 to 30%. In an attempt to improve this process, a procedure was suggested in which the operation took place in an autoclave under pressure and the resultant liquid slurry was maintained at 220° to 230° C. for three hours at a pressure of 17 to 18 atmospheres. This method was quite burdensome and difficult to operate, particularly on a relatively large commercial scale and experience has shown that the yield of 8-hydroxy quinoline was not more than about 50%.

The present invention utilizes a process where-

2 in quinoline 8-sulfonic acid, or its alkali metal or alkaline earth metal salts, is reacted with sodium hydroxide, it being among the objects of the present invention to provide a process wherein the reaction takes place in the semi-solid phase without fusion of the constituents.

It is also among the objects of the present invention to provide a process wherein a relatively high temperature is maintained for a relatively short time whereby a highly efficient operation is obtained.

It is still further among the objects of the present invention to provide a process which is of simple character, does not require the use of high pressure and may be operated by relatively unskilled labor with resulting very high yields of 8-hydroxy quinoline.

In the practice of the present invention, there is provided a mixture of sodium hydroxide in divided form, for instance, in the form of flakes, powder or pellets. The proportion or ratio of the sodium hydroxide to the quinoline 8-sulfonic acid is relatively critical and the amount of said hydroxide by weight is 1.2 to 2 parts for each part of the quinoline 8-sulfonic acid. If a lesser proportion of the hydroxide is used, it becomes difficult to completely convert the quinoline 8-sulfonic acid and if a higher amount of the alkali is used, the yields are reduced.

30 The reaction mixture includes a very small amount of water. The water is present in not over 4% based on the sodium hydroxide present and preferably between .5% and 4% of water is used. It has been found that the ratio of sodium hydroxide to water by weight should be 35 to 45 parts of sodium hydroxide to one part of water for the best results. This ratio is sufficient so that at the temperature of reaction, the sodium hydroxide is in the semi-solid phase and the reaction is a semi-solid-solid type of reaction.

Usually the operation is conducted in an open vessel or in a vented vessel to avoid superatmospheric pressure as it has been determined that high pressures are unnecessary for the reaction under the present conditions. The temperatures used range from 250° C. up to about 290° C. The reaction starts slowly at about 250° C. and reaches a maximum at about 290° C. If lower temperatures are used, the reaction is so slow as to practically not take place, while if the temperature is raised to substantially above 290° C., the yield of 8-hydroxy quinoline is reduced to a substantial extent depending on the temperature used.

Only a short time is required for the operation and the mixture is maintained at the reaction

temperature for not over thirty minutes and usually between five and thirty minutes. In most operations, from seven to ten minutes has been found eminently satisfactory to give effective results. In conducting the reaction the alkali metal hydroxide and the water are first heated to the reaction temperature, the mixture is stirred or agitated continuously and the quinoline 8-sulfonic acid or its aforesaid salts is added into the mixture in a very short time while continuing the agitation. In a few minutes, the reaction is complete and the product may be treated in any well-known manner to recover the pure 8-hydroxy quinoline.

The following is a specific example of one method of operation of the present invention.

The reaction vessel may be an open kettle placed under a hood or a closed vessel provided with an exit pipe for gases. There is introduced into the reaction vessel 335 parts by weight of flake sodium hydroxide and 8.4 parts by weight of water and the mixture is heated to 270° C. The vessel is provided with a mechanical stirrer and the mixture is stirred vigorously while adding thereto 210 parts by weight of powdered quinoline 8-sulfonic acid. The molecular ratio of sodium hydroxide to quinoline 8-sulfonic acid is 8.35 to 1. The stirring is continued after the addition of the quinoline 8-sulfonic acid, whereby the sodium salt of quinoline 8-sulfonic acid which is formed in the initial stages of the reaction is gradually converted into a light yellow salt of 8-hydroxy quinoline. The reaction takes approximately ten minutes and the completeness thereof is gauged by the light yellow color of the product.

The resulting mixture is cooled and is broken up into relatively small pieces. They are introduced into an excess of dilute aqueous sulphuric acid with stirring to dissolve the product. The resulting mixture is then adjusted to pH 7 by the use of a dilute solution in water of sodium hydroxide. The solution is steam distilled whereby a pure 8-hydroxy quinoline is obtained in the distillate. The latter is allowed to cool, the liquid is removed therefrom by suction filtration and the product is dried. The 8-hydroxy quinoline so obtained has a melting point of 71° to 73° C. and the yield is about 132 parts by weight or 91% based on the starting material.

There are numerous advantages inherent in the present process, including the fact that the reaction being in the semi-solid state is more readily controlled and a high temperature of reaction for a short time avoids the possibility of the formation of decomposition products which have in the past been formed at lower temperatures and longer times of reaction. The yield in every case is very high and yields of 95 and 96% are not uncommon. Because of the speed of the reaction and the lack of necessity of close control of conditions, the operation becomes simple and a relatively small amount of equipment is capable of producing relatively large yields.

Although the invention has been described setting forth a single specific embodiment thereof, such example does not limit the invention but is intended to illustrate the character thereof. Many variations in the details may be made within the spirit of the invention, as for example, alkali metal or alkaline earth metal salts may replace the free quinoline-8-sulfonic acid. The solution of the product may be in some other acid than sulphuric, such as hydrochloric acid solution. Also instead of allowing the reaction prod-

uct to cool before dissolving it in the acid for the refining operation, the hot reaction product may be introduced into the dilute aqueous acid with good results. If the higher temperatures of reaction are used, the time of reaction is correspondingly less within the limits set forth above.

The reaction product, while still at or near the reaction temperature, may be dissolved in water, thus freeing the sodium salt of 8-hydroxy quinoline from the excess of sodium hydroxide, by precipitation from the sodium hydroxide solution. After separation of the salt, the sodium hydroxide in the solution may be recovered for re-use.

The process may also be altered whereby the mixture of the quinoline 8-sulfonic acid, sodium hydroxide and water is first made in the cold and the mixture is passed rapidly through a heated reaction vessel, heated at such a rate as to bring the temperature up to above 250° C. in a very few minutes. The mixture is held at said temperature for a few minutes in order to complete the reaction and the product may then be utilized in any suitable manner. It is also possible to operate the reaction in a continuous manner by making a mixture of sodium hydroxide and water, passing the same continuous through a heated tube or trough fitted with a screw conveyor and at a desired point during the passage of the alkali through the reaction vessel, where the temperature has been raised to the proper point, the powdered quinoline-8-sulfonic acid, or its aforesaid salts, is introduced and is carried along by the alkali. Simultaneously, the operation of the screw conveyor thoroughly and uniformly mixes the constituents together and the reaction goes to completion in a short time.

These and other changes in the details of the invention may be made within the principles herein set forth and the invention is therefore to be broadly construed and not to be limited except by the character of the claims appended hereto.

We claim:

1. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, whereby the sodium salt of 8-hydroxy quinoline is formed.

2. A method of making 8-hydroxy quinoline which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, agitating the same, whereby the sodium salt of 8-hydroxy quinoline is formed, and dissolving the product in dilute mineral acid to form 8-hydroxy quinoline.

3. A method of making 8-hydroxy quinoline which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, agitating the same,

whereby the sodium salt of 8-hydroxy quinoline is formed, dissolving the product in dilute mineral acid to form 8-hydroxy quinoline, and steam distilling said 8-hydroxy quinoline.

4. A method of making 8-hydroxy quinoline which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, agitating the same, whereby the sodium salt of 8-hydroxy quinoline is formed, and dissolving the product in dilute mineral acid while at approximately the reaction temperature to form 8-hydroxy quinoline.

5. A method which comprises providing divided sodium hydroxide, adding thereto 0.5 to 4% of water, heating said mixture to a temperature of 250°-290° C. without fusion, introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, whereby the sodium salt of 8-hydroxy quinoline is formed.

6. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture after it has reached said temperature, the ratio of sodium hydroxide to said sulphonic acid being 1.2-2 to 1, and agitating the same, whereby the sodium salt of 8-hydroxy quinoline is formed.

7. A method which comprises providing divided sodium hydroxide, adding thereto 0.5 to 4% of water and in the proportion of 1 to 35-45 parts by weight of the sodium hydroxide, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, whereby the sodium salt of 8-hydroxy quinoline is formed.

8. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, the ratio of sodium hydroxide to quinoline-8-sulfonic acid by weight being 1.2-2 to 1, whereby the sodium salt of 8-hydroxy quinoline is formed.

9. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, maintaining the reaction temperature for from 5 to 30 minutes, whereby the sodium salt of 8-hydroxy quinoline is formed.

10. A method which comprises providing di-

vided sodium hydroxide, adding thereto 0.5 to 4% of water, heating said mixture to a temperature of about 270° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, maintaining the reaction temperature for about 7 to 10 minutes, whereby the sodium salt of 8-hydroxy quinoline is formed.

11. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same while maintaining the reactants in the semi-solid state, whereby the sodium salt of 8-hydroxy quinoline is formed.

12. A method which comprises providing divided sodium hydroxide, adding thereto 0.5 to 4% of water, advancing said mixture continuously while heating said mixture to a temperature of 250° C. to 290° C. introducing a compound taken from the group consisting of quinoline-8-sulfonic acid and its alkali and alkaline earth metal salts into said mixture continuously at a point in the travel of said mixture where a reaction temperature exists while continuously agitating the same, the ratio of sodium hydroxide to said sulphonic acid being 1.2-2 to 1, whereby the sodium salt of 8-hydroxy quinoline is formed.

13. A method which comprises providing divided sodium hydroxide, adding thereto 0.5 to 4% of water, introducing a compound taken from the group consisting of quinoline-8-sulfonic acid and its alkali and alkaline earth metal salts into said mixture, the ratio of sodium hydroxide to said sulphonic acid being 1.2-2 to 1, then rapidly heating the same to a temperature of 250° C. to 290° C., while agitating, whereby the sodium salt of 8-hydroxy quinoline is formed.

14. A method which comprises providing divided sodium hydroxide, adding thereto 0.5 to 4% of water, heating said mixture to a temperature of 250° C. to 290° C., introducing a compound taken from the group consisting of quinoline-8-sulfonic acid and its alkali and alkaline earth metal salts into said mixture, the ratio of sodium hydroxide to said sulphonic acid being 1.2-2 to 1, and agitating the same, whereby the sodium salt of 8-hydroxy quinoline is formed, dissolving the reaction product while at reaction temperature in water, whereby said sodium salt is freed from the excess of sodium hydroxide.
